REUBEN ADAMS AND J. DAVID SHEETZ, OF HEIDLEBERG TOWNSHIP, PENNSYLVANIA.

Letters Patent No. 91,699, dated June 22, 1869; antedated December 22, 1868.

IMPROVEMENT IN HAY-SPREADERS.

The Schedule referred to in these Letters Patent and making part of the same.

To all whom it may concern:

Be it known that we, REUBEN ADAMS and J. DAVID SHEETZ, of Heidleberg township, in the county of Berks, and in the State of Pennsylvania, have invented an Improvement in "Hay-Spreaders," and do hereby declare that the following is a full, clear, and exact description thereof, reference being had to the accompanying drawings, and to the letters of reference marked thereon.

Our invention relates to that class of machines known as hay-spreaders; and consists in the construction and general arrangement of the different parts constituting the same.

In order to enable others skilled in the art to which our invention appertains, to make and use the same, we will now proceed to describe its construction and operation, referring to the annexed drawings, which form a part of this specification, and in which—

Figure 1 is a plan view, and

Figure 2, a side elevation in section.

A A represent two end-bars, connected at or near the front ends by a beam, B, to which the shafts C C are secured.

To the side-bars A A are secured the axles a a, for the driving-wheels D D.

On top of the side-bars A A is secured a beam, or bar, E, and at a suitable point on the under side of the beam E is secured a bar, F, running parallel with the side-bars A A. The front end of the bar F is secured to the beam B.

Between the rear ends of the side-bars A A are placed two crank-shafts G and H, the inner ends of both having their bearings in the rear end of the bar F, and the outer ends passing through the side-bars A A.

The outer ends of the crank-shafts G and H are provided with loose pinions b b, which gear into cog-wheels I I, secured to the inner sides of the driving-wheels D D.

By moving the collars c c, which work on feathers on the outer ends of said crank-shafts, they are made to revolve or not, as may be desired. The collars c c are moved to or from the pinions b b by means of the levers J J.

These levers J are held in either position required, by means of movable pins x, on the forward ends of the bars A, so that the machine may be held either in or out of gear, by the pins acting against the levers.

On the lower side of the bar B is a series of hinged stirrups, d d, to the lower ends of which bars K K are pivoted, the rear ends of said bars being pivoted to the crank-shafts G H; that is, these crank-shafts pass through the rear ends of said bars.

On each side of the rear ends of the bars K K are secured metal bars e e, which project towards the rear, and between which the arms f f are pivoted.

The upper ends of the arms f f are connected with the bar E, by means of other arms, h h, pivoted to said bar and to the arms f f.

The lower ends of the arms f f, which extend below the metal bars e e, are forked, and therein are pivoted the shanks i i, said shanks being provided with the usual forks L L.

The upper part of the shank i, above the pivot-point, is acted upon by a spring, m, which is secured to the rear side of the arm f, and extends downwards between the bars e e, as shown in fig. 2.

The driver's seat M is supported by any suitable means from the bar E, near one end thereof.

Having thus fully described our invention, What we claim as new, and desire to secure by Letters Patent, is—

1. The arrangement of the beam K with metal bars e e, arms f and h, shank i, and spring m, all as shown and described.

2. The arrangement of the levers J and pins x, collars c, and pinions b, with the two crank-shafts G H and their forks or spreaders L, all constructed and operated substantially as set forth.

In testimony that we claim the foregoing, we have hereunto set our hands, this 24th day of September, 1868.

REUBEN ADAMS.
J. DAVID SHEETZ.
